SHOE SUPPORTING JACK

Alfred R. Morrill, Beverly, Mass., assignor to
 United Shoe Machinery Corporation, Flemington, N. J., a corporation of New Jersey

Application January 31, 1945, Serial No. 575,473

11 Claims. (Cl. 12—127)

1

The present invention relates to shoe supporting jacks for use in the manufacture of shoes, and more particularly to a novel and improved construction and arrangement of the mechanism for securing the several cooperating parts of the jack in the closed shoe supporting position of the jack preparatory to and during the performance of any manufacturing operation upon the jacked shoe.

The jack herein disclosed as embodying in a preferred form the several features of the present invention is of the general type illustrated in the Morrill Patent No. 2,331,130, dated October 5, 1943, for a Shoe supporting jack, and in the Morrill Patent No. 2,323,346, dated July 6, 1943, for a Machine for use in the manufacture of shoes, comprising a shoe support which is secured to a rotatable jack spindle or frame, a toe rest vertically adjustable on the shoe support, a heel support movable toward and from the toe rest, a last pin and a last pin carrier pivotally mounted in the heel support for tilting movement to engage the toe of the jacked shoe against the toe rest, toe centering grips carried by the shoe support movable toward and from each other and arranged to engage opposite sides of the toe portion of the shoe, a jacking lever, and connections actuated by the jacking lever for tilting the last pin carrier, for moving the toe centering grips against the shoe, and for advancing the heel support to and securing the shoe firmly in position on the jack. The shoe is initially located on the jack and a corresponding adjustment of the several cooperating jacking elements engaging the shoe is obtained by means of a fixed toe gauge against which the shoe is brought prior to the actuation of the jacking lever. The jacking lever is now moved by the operator to secure the shoe in the jacked position, and acts through an eccentric pawl and ratchet connection having a tightening action to draw together two slide elements, one being the heel support which is forced forwardly, and the other being an operating ratchet for the toe centering grips which are thus moved tightly against the sides of the shoe toe. The slide elements referred to, are freely movable with relation to the shoe support on which they are mounted, so that the positions of the heel support and toe centering grips relative to one another and to the jack support may be automatically established through engaging contact with the lasted shoe.

The organization of the mechanism for clamping the lasted shoe on the jack including the construction and arrangement of this mechanism, as

heretofore employed, for forcing the shoe forwardly against the toe rest and for tightening the several cooperating parts to a like extent one against the other while these parts remain freely movable with relation to the jack support, has been found to have certain drawbacks. Experience has shown that it is not always possible to seat the toe of the shoe firmly against the fixed toe gauge, so that the heel slide occasionally slips or is displaced forwardly during the subsequent operation upon the shoe. As the toe and heel assemblies of the jack are tightened one against the other, the effect of such movement of the heel support is to loosen both the heel and toe assemblies of the jack, so that the shoe is insecurely held and may even become unjacked with attendant risk of injury to the shoe and to the shoe operating mechanism to which the shoe is being presented.

It is the object of the present invention to provide a novel and improved construction and arrangement of the jacking mechanism which will provide for the free adjustment of the several jacking elements with respect to one another, and will thereafter cause the jack tightening and clamping mechanism to be locked securely in the jacking position with relation to the jack support.

More specifically, it is an object of the invention to provide in a construction of this general type, fastening means for the heel slide and last pin tilting mechanism which is unaffected by any looseness which may subsequently develop between the shoe and fixed toe gauge or in the gripping action of the toe centering grips, and will assist to maintain the jacked shoe securely in its clamped position.

With these and other objects in view as may hereinafter appear, the several features of the invention consist in the devices, combinations and arrangement of parts hereinafter described and claimed, which together with the advantages to be obtained thereby will be readily understood by one skilled in the art from the following description taken in connection with the accompanying drawings, in which Fig. 1 is a view in elevation and partly in section of the shoe supporting portion of the jack with a lasted shoe thereon and the parts in shoe clamping position; Fig. 2 is a sectional plan view taken on the line 2—2 of Fig. 3, to illustrate particularly the relation of the heel slide, its guideway and the mechanism controlled by the jacking lever to secure the heel slide against its ways; Fig. 3 is an enlarged sectional view taken on the line 3—3 of Fig. 2, illustrating particularly the heel assembly of the jack, the

jacking lever and toggle connection with the heel carrier pin; Fig. 4 is a sectional view taken on the line 4—4 of Fig. 3, to illustrate particularly the operation of the heel slide clamping device; Fig. 5 is a sectional view substantially similar to Fig. 3, but on a smaller scale and with the jack in the open position; and Fig. 6 is a sectional view taken on the line 6—6 of Fig. 5, to illustrate particularly the toe grips and their supporting and operating means.

The jack illustrated in the drawings is of the general type shown in the patent to Morrill No. 2,331,130 above referred to, and comprises generally a jack support 10 which is rigidly secured to a rotatable jack frame or spindle indicated at 12.

The means for supporting the shoe on the jack comprise a toe rest 14 and a heel support 16, the toe rest being mounted on the jack frame 10 so as to be capable of vertical movement only heightwise of the shoe, and the heel support being movable toward and from the toe rest to accommodate shoes of different sizes. To locate the shoe in a predetermined longitudinal position on the jack, a fixed toe gauge 18 is provided consisting of a block secured to and extending upwardly from the forward end of the jack support 10.

The toe portion of the shoe is also located and held in proper position on the jack by means of toe grips or clamps, which toe grips are arranged to move toward and from each other and to engage opposite sides of the toe portion of the shoe. Each toe grip consists of a substantially vertically arranged plate 20 provided with a depending stud fitted to rotate in a block 22 which in turn is pivotally mounted to turn on a horizontally arranged bearing pin 24 on the jack support 10. Each plate 20 is acted upon by a light spring 26 which tends to rotate the rear end of the plate inwardly toward the shoe. The toe grips 20 are arranged to be moved together, and are normally pressed inwardly by spring-pressed plungers 28 which engage yieldingly against outwardly extending abutments on the blocks 22, and are further provided with rack teeth engaging a pinion shaft 30 extending horizontally across the jack support 10. The pinion shaft 30 is also arranged to mesh with a rack in a toe grip control slide 32 mounted in a guideway 34 in the jack support 10. A ratchet 36 formed in the under side of the toe grip control slide 32 is arranged to be engaged by a pawl 38 carried on the eccentric hub of the jacking lever 39 mounted on the heel support 16. The jacking lever 39 and pawl 38 form part of the mechanism for tightening the jacked shoe in place, herein-after more fully to be described.

The heel support 16 comprises a bifurcated slide mounted to move toward and from the toe rest in guideways 41 formed on the under side and in rearwardly projecting side rails forming part of the jack support 10. Upon the heel support 16 is mounted a last pin carrier 40 provided with an upwardly projecting last pin to enter the last pin hole of a shoe last. The last pin carrier 40 is fitted into a vertical slot formed in the rear end of the heel support 16, and is mounted upon a horizontal pin 42 so as to be capable of a tilting movement to press the toe of a shoe downwardly against the toe rest. The lower portion of the last pin carrier 40 is slotted to receive an actuating arm 44 which is pivotally supported at its upper end upon the pin 42. The arm 44 carries a pawl 46 for engagement with ratchet teeth

48 on the bottom face of the last pin carrier 40. A leaf spring 49 secured to the actuating arm 44 for engagement against the base of the slotted portion of the last pin carrier 40 tends to rock the last pin carrier counterclockwise away from the toe rest and to maintain the ratchet teeth thereon engaged against the pawl 46.

In order to actuate the pawl toward and from the ratchet teeth and to move the pawl in a direction to tilt the last pin and carrier, the pawl 46 is provided with projections 54, 56 acting against a vertically movable wedge 58 and a wedge supporting surface 60 on the heel support slide 16 respectively. The wedge is connected through a pin and slot connection with one arm of a lever 62 on the heel support, the other arm of which is connected by means of an actuating link 64 with an arm 65 of the jacking lever 39. The actuating arm 44 is urged yieldingly in a counterclockwise direction away from the toe rest by means of a plunger 66 carried on the heel support 16 and spring-pressed upwardly into engagement with a shoulder on the arm 44.

Adjustment of the position of the toe rest 14 vertically in accordance with the size of shoe being operated upon is determined automatically by the position of the heel support 16 by means of a connecting rod 68, the forward end of which is arranged to slide between suitably shaped surfaces on the jack support and the under side of the toe rest 14.

In the operation of jacking the shoe, the several operating parts of the jack including the centering toe grips 29, the heel support 16, the toe rest 14 and the last pin carrier 40 are tightened together and locked in the tightened position by means of the manually operable jacking lever 39. In this operation, a lasted shoe is placed on the last pin and is tilted forwardly and down by the operator against the toe rest 14, and is moved longitudinally until the toe is brought firmly against the stationary toe gauge 18, this movement acting to bring the several operating parts substantially to their closed or jacking position. The jacking lever 39 is now moved to its closed position so that the toggle connection provided by the link 64 and the jacking lever 39 is rendered operative to raise the wedge 58 to engage the pawl 46 with the ratchet teeth on the last pin carrier 40 to force downwardly and to lock the toe portion of the shoe against the toe rest 14. At the same time the pawl 38 carried on the eccentric hub of the jacking lever is moved rearwardly with relation thereto, thus drawing together the toe grip control slide 32 and the heel support 16 to further tighten the toe grips 20 against the sides of the shoe toe, and at the same time to force the shoe still more firmly in the forward direction against the toe grips 29 and fixed toe gauge 18. It will be noted that all of these parts are freely movable with relation to the jack support 10, and are moved with relation to one another against the shoe, which in turn is located only with reference to the toe gauge 18. The operation of the jacking lever as thus far described and in accordance with the illustration of the Morrill patents above referred to, causes the several operating parts to be tightened only with relation to one another against the shoe.

In accordance with the present invention, an added locking or fastening means is provided which is rendered operative by movement of the jacking lever 39 to its closed or jacking position to secure the heel support directly to the jack support 10. Further in accordance with

the invention, the additional locking means referred to, is arranged to be rendered operative only after the several cooperating parts, each freely movable with respect to the jack support 10, have been tightened against the shoe. As shown in the drawings, the heel support or slide 16 is formed with two slots 70 which extend along the greater portion of the length of the slide so that the outer edge portions of the slide formed with guide surfaces for engagement with the guideways 41 may be readily sprung outwardly into locking engagement therewith. A portion of the tongue 72 formed by the slots 70 is cut away to provide an aperture 74 within which is mounted the jacking lever 39. A pair of spring plates 76 mounted in the slots 70 are arranged with their ends projecting into the aperture 74, and these ends are bent inwardly to provide spring members which engage with the knuckle provided by the bifurcated end of the heel tilting toggle lever 64 at the point of its pivotal connection with the arm 65 of the jacking lever 39 when the jacking lever is moved to the jacking position illustrated in the several figures of the drawings. As best shown in Figs. 3 and 4, the knuckle end portion of the lever 64 is rounded or cammed at 78 to facilitate the movement of the knuckle between the spring members 76. As will be evident from an inspection of the drawings, the final increment of movement of the jacking lever 39 to the jacking position will cause the knuckle formed by the pivotal connection of the lever 64 and arm 65 of jacking lever 39 to move between the spring plates 76, forcing them outwardly and thus exerting a strong outward pressure upon the two side walls of the heel support or slide 16 which causes the slide to be jammed or locked against movement on the guideways 41, so that the heel slide is firmly fixed with relation to the jack support 10.

With the construction and arrangement of the jack tightening and clamping mechanism above described, it will readily be seen that a more secure clamping and holding of the jacked shoe is obtained without any sacrifice in the freedom with which the several parts of the heel and toe assemblies of the jack are permitted to adjust themselves in clamping relation to the lasted shoe. Any tendency of the heel slide to be displaced forwardly as a result of increased pressure of the shoe toe against the toe gauge or of any undetected looseness in the position of the toe grips is wholly obviated, and the risk that any appreciable loosening of the heel and toe assemblies of the jack may take place is correspondingly reduced.

The nature and scope of the invention having been indicated, and an embodiment of the invention having been specifically described, what is claimed is:

1. A shoe supporting jack comprising a jack frame, a toe supporting assembly including a toe gauge stationary on the frame, toe grips engaging opposite sides of the shoe toe, and a slide carried on the frame movable to tighten said grips, a heel supporting and clamping assembly including a guideway on the frame, a heel support slidably mounted in the guideway to move in a direction opposite to the direction of movement imparted to the slide to tighten the shoe against the toe gauge and grips, and means including a jacking lever actuatable for relatively moving said heel support and slide

to tighten said assemblies one against the other, and thereafter to secure the heel support rigidly directly to the jack frame.

2. A shoe supporting jack comprising a jack frame, a stationary toe gauge on the frame, a heel supporting and clamping assembly including a guideway on the frame, a heel support slidably mounted in the guideway for movement in one direction to engage a shoe toe against the toe gauge, a toe supporting assembly comprising a pair of toe grips and a toe slide movable in a direction opposite from said direction of movement of the heel slide to tighten the toe grips, means including a jacking lever movable to tighten said heel support and slide one against the other relatively in opposite directions to tighten both said heel and toe assemblies, and means rendered operative by the movement of said jacking lever to rigidly secure the heel support directly to the jack frame.

3. A shoe supporting jack comprising a frame, a toe supporting assembly including a toe gauge mounted on the frame, toe grips arranged for gripping engagement with opposite sides of the shoe toe, a heel supporting and clamping assembly including a heel support carried by the frame movable to engage the shoe toe against the toe gauge, and control means for tightening the jack to secure a shoe on the jack comprising a ratchet and pawl mechanism for tightening the heel support and shoe against the toe gauge, and a clamping device operative thereafter for rigidly clamping the heel support in its tightened position directly to the jack frame.

4. A shoe supporting jack comprising a frame, a toe supporting assembly including a toe gauge mounted on the frame, toe grips arranged for gripping engagement with opposite sides of the shoe toe, a heel supporting and clamping assembly including a heel support carried by the frame movable to engage the shoe toe against the shoe gauge, and control means for tightening the jack to secure the shoe on the jack comprising a jacking lever movable between release and jacking positions, a ratchet and pawl mechanism actuated by movement of the jacking lever for tightening the heel support and shoe against the toe gauge, and a clamping device rendered operative by the continued movement of the jacking lever thereafter for rigidly clamping the heel support in the tightened position directly to the jack frame.

5. A shoe supporting jack comprising a frame, a shoe supporting assembly including a toe gauge mounted on the frame, toe grips arranged for gripping engagement with opposite sides of the shoe toe, a heel supporting and clamping assembly including a guideway on the frame, a heel support slidably mounted in said guideway on the frame for movement longitudinally of the shoe to engage the shoe toe against the toe gauge, and control means for tightening the jack to secure the shoe on the jack comprising a jacking lever movable between release and jacking positions, a ratchet and pawl mechanism rendered operative by movement of the lever toward jacking position for moving the heel support on the guideway to tighten the shoe against the toe gauge, and a clamping device actuated by continued movement of the jacking lever to the jacking position for rigidly clamping the heel support directly to the guideway.

6. A shoe supporting jack comprising a jack frame, a toe gauge stationary on the frame, a heel supporting and clamping assembly includ-

ing a heel support movable on the frame to tighten the shoe against the toe gauge, a toe supporting and clamping assembly including toe grips and a member movable on the frame in a direction opposed to that of said heel support to tighten said grips against the shoe, and tightening means operable when actuated to tighten said heel support and member one against the other independently of said frame, and thereafter to secure said heel support rigidly directly to the frame.

7. A shoe supporting jack comprising a frame, a stationary toe gauge mounted on the frame, a toe rest, a heel support carried on the frame movable toward and from the toe gauge and toe rest lengthwise of a shoe supported on the jack, a last pin, a last pin carrier mounted to tilt on the heel support, toe centering grips movable toward and from each other arranged to engage and grip opposite sides of the toe portion of a shoe, a member provided with a ratchet mounted on the frame and connected to move with the toe grips, a jacking lever pivoted on the heel support for movement between release and locking positions, connections actuated by the jacking lever for tilting the last pin to press the toe of a lasted shoe placed on the jack against the toe rest, a pawl cooperating with said ratchet and arranged to be actuated by the jacking lever for relatively moving the member and heel support to tighten the grips and to tighten the shoe against the toe gauge and grips, and a locking device actuated by the jacking lever for securing the heel support in the tightened shoe clamping position rigidly directly to the frame.

8. A shoe supporting jack comprising a frame, a stationary toe gauge mounted on the frame, a toe rest, a heel support carried on the frame movable toward and from the toe gauge and the toe rest lengthwise of a shoe supported on the jack, a last pin, a last pin carrier mounted to tilt on the heel support, toe centering grips movable toward and from each other arranged to engage and grip opposite sides of the toe portion of a shoe, a member carried on the frame and connected to move with the toe grips, said heel support and member being arranged for movement relatively for tightening the heel support and toe grips respectively, a jacking lever, means actuated by the jacking lever for tilting the last pin to press the toe of a lasted shoe placed on the jack against the toe rest, tightening means actuated by the jacking lever for relatively moving the heel support and member to tighten the same one against the other, and means actuated by the jacking lever for securing the heel support to the frame in the tightened position.

9. A shoe supporting jack comprising a frame, a toe supporting assembly including a toe gauge stationary on the frame, and toe grips arranged for gripping engagement with opposite sides of the shoe toe, a heel supporting and clamping assembly including a guideway on the frame and a heel support slidably mounted in said guideway for movement longitudinally of the shoe to engage the shoe toe against the toe gauge, said heel support being slotted from one end along a substantial portion of its length to provide a pair of flexible slide elements for engagement within the guideway, and control means for tightening the jack to secure the shoe on the jack comprising a jacking lever carried on the heel support

movable between release and jacking positions, tightening means rendered operative by movement of the lever toward jacking position for moving the heel support on the guideway to tighten the shoe against the toe gauge, and a clamping element associated with the jacking lever arranged upon movement of the jacking lever to the jacking position to move between and flex said slide elements against the guideway.

10. A shoe supporting jack comprising a frame, a toe supporting assembly including a toe gauge stationary on the frame, and toe grips arranged for gripping engagement with opposite sides of the shoe toe, a heel supporting and clamping assembly including a guideway on the frame and a heel support slidably mounted in said guideway for movement longitudinally of the shoe to engage the shoe toe against the toe gauge, said heel support being slotted from one end along a substantial portion of its length to provide a pair of flexible slide elements for engagement within the guideway and with an aperture formed therebetween, a pair of spring members supported with relation to said slide elements within said aperture, and control means for tightening the jack to secure the shoe on the jack comprising a jacking lever mounted on the heel support movable between release and jacking positions, tightening means rendered operative by movement of the lever toward jacking position for moving the heel support on the guideway to tighten the shoe against the toe gauge, and a clamping element actuated by continued movement of the jacking lever to the jacking position to engage said spring members in said aperture to force the flexible slide elements against the guideway.

11. A shoe supporting jack comprising a frame, a stationary toe gauge mounted on the frame, a toe rest, a guideway on the frame, and a heel support slidable in the guideway and bifurcated along a substantial portion of its length to provide relatively flexible slide elements for engagement with the guideway for movement toward and from the toe gauge and toe rest lengthwise of a shoe supported on the jack, a last pin, a last pin carrier mounted to tilt on the heel slide, toe centering grips movable toward and from each other arranged to engage and grip opposite sides of the toe portion of a shoe, a member provided with a ratchet mounted on the frame and connected to move with the toe grips, a jacking lever pivoted on said bifurcated heel support for movement between release and locking positions, connections including an arm having a pivotal connection with the jacking lever for tilting the last pin to press the toe of the lasted shoe placed on the jack against the toe rest, a pawl cooperating with said ratchet and arranged to be actuated by the jacking lever for relatively moving the lever and heel support to tighten the grips and to tighten the shoe against the toe gauge and grips, and a locking device comprising a pair of spring arms supported with relation to said flexible slide elements and arranged to be acted upon by said pivotal connection upon movement of the jacking lever to the locking position to relatively flex said slide elements against the guideway for securing the heel support in the tightened shoe clamping position rigidly to the guideway.
